ANTISTORAGE CONTROL APPARATUS FOR
RAILWAY TRACK SWITCHESTheodore L. Carlson, Richmond, Va., assignor to
The Union Switch and Signal Company, Swiss-
vale, Pa., a corporation of Pennsylvania

Application January 11, 1950, Serial No. 137,996

9 Claims. (Cl. 246—219)

1

My invention relates to anti-storage control apparatus for railway track switches. More particularly, my invention relates to an arrangement for effecting operation of a railway track switch only if apparatus responsive to traffic conditions adjacent the switch is energized at the time that manual control apparatus is conditioned for effecting operation of the switch.

In control apparatus for railway track switches and signals embodying control levers which are mechanically interlocked, each switch control lever is, according to well-known practice, commonly equipped with an electric lock which can be energized for releasing the associated switch lever only if a switch locking relay which is responsive to traffic conditions adjacent an associated switch is energized. It follows that such a switch control lever can be moved from either of its control positions to the other only at such times as the associated switch locking relay is energized.

On the other hand, in control apparatus for railway track switches and signals in which the control levers are not interlocked but are free to be moved at any time, the switch control levers can be moved while the associated switch locking relays are deenergized. The circuits for operating the track switches, however, cannot become energized for effecting movement of the switches until the associated switch locking relays become energized.

It has been found, though, that under some conditions, there may be a momentary loss of shunt of a track circuit, so that an associated track relay may momentarily close its front contacts and effect energization of an associated switch locking relay while the associated track section is occupied. If the switch control arrangement were such that the switch control could be stored, that is, if it were such that a switch operating circuit could become closed during a loss of shunt period which would effect movement of a switch because of previous movement of a switch control lever during occupancy of a track section, there would be a dangerous condition.

An object of my invention, therefore, for protecting against such dangerous operation of a railway track switch, due to a momentary loss of shunt, is to provide a switch control arrangement such that the switch control cannot be stored.

A feature of my invention for attaining this object is the provision of an arrangement embodying an electrical control device, shown in

2

the accompanying drawing as an energy storing device such, for example, as a capacitor D, which becomes energized, while a switch control lever is being moved from one of its extreme or switch controlling positions to the other, only if an associated switch locking relay is energized. Upon further movement of the switch control lever to a switch controlling position, a switch control relay becomes energized, for effecting corresponding operation of an associated switch in response to the capacitor in its energized or charged condition, only if the associated switch locking relay is still energized.

With apparatus embodying my invention, if, while a given switch locking relay is deenergized, an associated switch control lever is moved from either of its extreme positions to the other, the associated switch operating circuit cannot become closed for effecting a corresponding movement of an associated switch. If the switch control lever is then left in the position to which it was moved while the associated switch locking relay was deenergized, the switch operating circuit for moving the switch to a corresponding position will still not become closed when the switch locking relay subsequently becomes energized either due to a loss of shunt of the track section or due to the track section having become vacated. With apparatus embodying my invention, a switch operating circuit can become closed only if the associated switch control lever is moved to a corresponding position while the associated switch locking relay is energized.

I shall describe one form of apparatus embodying my invention, and shall then point out the novel features thereof in claims.

The accompanying drawing is a diagrammatic view showing one form of apparatus embodying my invention, in which a capacitor becomes charged, while a switch control lever is being moved from one of its control positions to the other, only if an associated switch locking relay is energized. If the capacitor has become charged, a switch control relay becomes operated by energy discharging from the capacitor for closing a corresponding switch operating circuit when the associated control lever reaches the associated control position.

Similar reference characters refer to similar parts in the drawing.

Referring further to the drawing, two railway tracks are shown interconnected by a crossover track, at one end of which is a track switch designated by the reference character AW, and at

the other end of which is a track switch designated by the reference character BW.

The rails 1 and 1a of one of the tracks are divided by insulated joints 3 to form a track section, designated by the reference character AT, in which switch AW is located, and the rails 2 and 2a of the other track are divided by insulated joints 3 to form a track section, designated by the reference character BT, in which switch BW is located. Each of these track sections is provided with a track circuit including a suitable source of current, such as a battery 4, connected across the rails adjacent one end of the section, and a track relay, designated by the reference character R, preceded by the reference character AT or BT for the associated track section, connected across the rails adjacent the opposite end of the section.

A switch locking relay, designated by the reference character WLR, is controlled by a circuit which includes front contacts 5 and 6 of relays ATR and BTR, respectively, and which may also include contacts of other relays not shown in the drawing. Since track relays ATR and BTR are responsive to traffic conditions on the railway tracks adjacent switches AW and BW, it is well known that relay WLR, which is controlled by relays ATR and BTR, is also responsive to traffic conditions on the railway tracks adjacent switches AW and BW.

Switches AW and BW are provided with mechanisms designated by the reference characters AM and BM, respectively, by which the switches may be moved or operated, from the normal extreme position in which they are shown in the drawing, to the opposite or reverse extreme position. The switch mechanisms may be of any suitable design such, for example, as the well-known electro-pneumatic type or the electric motor type.

Movement of switches AW and BW between their extreme positions by mechanisms AM and BM, respectively, is controlled or effected by a switch control relay, designated by the reference character WSR, shown in the drawing as of the polar stick type having a normal control winding 9 and a reverse control winding 12. A contact 14 of relay WSR becomes closed in the normal position, in which it is shown in the drawing, in response to energization of normal control winding 9 of relay WSR, and remains closed in that position until the reverse control winding 12 of relay WSR becomes energized. When the reverse control winding 12 of relay WSR becomes energized, contact 14 of relay WSR becomes closed in the reverse position, which is shown in the drawing by a dotted line. When both windings of relay WSR are deenergized, contact 14 of relay WSR will remain closed in the position to which it was last previously operated.

A manually operable switch control device shown as a lever, designated by the reference character WV, has normal and reverse positions designated by the reference characters *n* and *r*, respectively, and has also the positions *a* and *e* between the *n* and *r* positions. Contacts operated by lever WV are represented on the drawing by circles. These contacts are closed when the lever WV is moved to the position designated by the letters shown in the corresponding circles. Contacts 10 and 13 of lever WV, the circular representations of which enclose the letters *n* and *r*, are accordingly closed when lever WV is in its *n* or *r* position, respectively. Contact 11 of lever WV is closed when lever WV is in the *a* position.

or the *e* position or at any point between these two positions.

An electrical control device which may be of the energy storing type such, for example, as a capacitor D, shown in the drawing, becomes energized by a circuit including contact 11 of lever WV and the front point of contact 7 of relay WLR.

The normal and reverse control windings 9 and 12, respectively, of relay WSR, are controlled by circuits which include contacts 10 and 13, respectively, of lever WV, and contacts 7 and 8 of relay WLR. These circuits are energized by the discharge of energy stored in capacitor D.

Having described, in general, the arrangement and control of the various parts of apparatus embodying my invention, I shall now describe the circuits and operation in detail.

As shown in the drawing, all parts of the apparatus are in the normal position, that is, track sections AT and BT are unoccupied, and therefore track relays ATR and BTR, respectively, are energized; each of the switches AW and BW is in its normal position; relay WLR is energized; lever WV is in its normal or *n* position; relay WSR is deenergized; capacitor D is in its deenergized or discharged condition; and contact 14 of relay WSR is closed in the normal position to the left, as shown in the drawing, although relay WSR is deenergized.

The circuit by which relay WLR is energized passes from terminal B of a suitable source of current such, for example, as a battery Q, shown in the drawing, through contacts 5 and 6 of relays ATR and BTR, respectively, and the winding of relay WLR to terminal N of the same source of current.

The circuit for energizing the normal control winding 9 of relay WSR is closed, this circuit passing from capacitor D, through the front point of contact 7 of relay WLR, contact 8 of relay WLR, winding 9 of relay WSR, and contact 10 of lever WV, back to capacitor D. Capacitor D is, however, in its deenergized or discharged condition, and, therefore, control winding 9 of relay WSR is not now energized by the circuit just traced.

I shall assume that, with apparatus arranged as shown in the drawing, a leverman decides to reverse switch AW and BW for a traffic movement over the crossover track. He will, therefore, move lever WV from the *n* position to the *r* position.

Contact 11 of lever WV will be closed while lever WV is being moved from the position *a* to the position *e* between positions *n* and *r*, so that capacitor D will be energized by a circuit passing from terminal B, through the front point of contact 7 of relay WLR, capacitor D, and contact 11 of lever WV to terminal N. Capacitor D, therefore, becomes charged by energy supplied to the circuit just traced from battery Q. The circuit for energizing capacitor D becomes opened when lever WV passes beyond position *e*.

When lever WV reaches its *r* position, a circuit becomes completed for energizing reverse control winding 12 of relay WSR by the discharge of energy which has been stored in capacitor D, this circuit passing from capacitor D, through the front point of contact 7 of relay WLR, contact 8 of relay WLR, winding 12 of relay WSR, and contact 13 of lever WV, back to capacitor D. Contact 14 of relay WSR is therefore moved to its reverse position, and remains closed in that position after capacitor D has been deenergized by being discharged.

Reverse operating circuits are therefore closed for mechanisms AM and BM, passing from terminal B, through contact 14 of relay WSR closed in the reverse position, and mechanisms AM and BM in multiple with each other, to terminal N. Switches AW and BW are therefore moved to their reverse position.

I shall next assume that the leverman decides to return switches AW and BW to their normal position. He will therefore return lever WV toward the *n* position. Capacitor D now becomes energized or charged again by energy supplied to the circuit previously traced, through contact 11 of lever WV, by battery Q.

When lever WV reaches the *n* position, the circuit previously traced through contact 10 of lever WV is completed for energizing the normal control winding 9 of relay WSR by the discharge of energy which has been stored in capacitor D. Contact 14 of relay WSR is therefore now moved to its normal position, and remains closed in that position after capacitor D has been deenergized by being discharged.

Normal operating circuits are therefore now closed for mechanisms AM and BM passing from terminal B, through contact 14 of relay WSR closed in the normal position, and the mechanisms AM and BM in multiple with each other, to terminal N. Switches AW and BW are therefore now returned to their normal position.

I shall now assume that, with all parts of the apparatus again in the normal condition, a car or short train enters section BT, and that while section BT is thus occupied, the leverman moves lever WV to the *r* position.

On account of section BT being occupied, relay BTR will be deenergized and, in turn, relay WLR will be deenergized because contact 6 of relay BTR is open. With relay WLR deenergized, contact 7 of the relay will be opened at its front point, and therefore the circuit previously traced for energizing capacitor D will not become closed. Furthermore, contact 7 of relay WLR will now be closed at its back point, so that any charge which there might have been in capacitor D will be dissipated through this back contact point and insure that capacitor D will be completely discharged.

If, while section BT is occupied, there should be a momentary loss of track shunt, so that relay BTR would close its contact 6, causing relay WLR to in turn also become energized for a brief period of time, the circuit previously traced for energizing reverse control winding 12 of relay WSR would become closed. On account of capacitor D not being charged, however, winding 12 of relay WSR would not become energized by this circuit and, therefore, contact 14 of relay WSR would remain closed in the normal position shown in the drawing.

It follows that, with my invention, there is no storage of control for the switch control relay WSR, so that operation of switch control lever WV while the traffic responsive switch locking relay WLR is deenergized will not cause relay WSR to become energized if relay WLR should subsequently become energized through a momentary loss of track shunt. If switches AW and BW could be operated due to a momentary loss of track shunt of section BT while this section is occupied, a car or train might be wrecked or at least derailed due to the switches being thrown under the car or train.

In order to effect operation of switches AW and BW to the reverse position after section BT becomes vacated, it is necessary for the lever-

man first to move lever WV to an intermediate position for closing contact 11 of lever WV in the circuit for energizing capacitor D, and then return lever WV to the *r* position.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Anti-storage control apparatus for a railway track switch comprising, in combination, a switch locking relay which is normally energized but which at times becomes deenergized in response to traffic conditions on the associated railway track adjacent said switch, a switch control lever having normal and reverse positions, a polar stick switch control relay, a capacitor, means controlled by said lever when between its said normal and reverse positions for charging said capacitor if said switch locking relay is energized, and means controlled by said lever in its normal and reverse positions for energizing said polar stick relay by current from said capacitor for controlling movement of said switch to normal and reverse positions respectively.
2. Anti-storage control apparatus for a railway track switch comprising, in combination, a switch locking relay which is normally energized but which at times becomes deenergized in response to traffic conditions on the associated railway track adjacent said switch, a switch control lever having normal and reverse positions, a polar stick switch control relay, a capacitor, means controlled by said lever when between its said normal and reverse positions for charging said capacitor if said switch locking relay is energized, and means controlled by said lever in its normal and reverse positions for energizing said polar stick relay by current from said capacitor if said switch locking relay is energized for controlling movement of said switch to normal and reverse positions respectively.
3. Anti-storage control apparatus for a railway track switch comprising, in combination, a switch locking relay which is normally energized but which at times becomes deenergized in response to traffic conditions on the associated railway track adjacent said switch, a switch control lever having normal and reverse positions, a polar stick switch control relay, a capacitor, means controlled by said lever when between its said normal and reverse positions for charging said capacitor if said switch locking relay is energized, means controlled by said lever in its normal and reverse positions for energizing said polar stick relay by current from said capacitor for controlling movement of said switch to normal and reverse positions respectively, and means controlled by said switch locking relay when deenergized for discharging said capacitor.
4. Control apparatus for a railway track switch comprising, in combination, a manually movable switch control device, a switch locking relay which is normally energized but which at times becomes deenergized in response to traffic conditions on the associated railway track adjacent said switch, an energy storing device, means controlled by operation of said manually movable control device for charging said energy storing device only while said switch locking relay is energized, and means energized by said energy

storing device controlled by further operation of said manually movable control device while said switch locking relay is energized for effecting corresponding movement of said railway track switch.

5. Control apparatus for a railway track switch comprising, in combination, a manually movable switch control device, a switch locking relay which is normally energized but which at times becomes deenergized in response to traffic conditions on the associated railway track adjacent said switch, an energy storing device, means controlled by operation of said manually movable control device for charging said energy storing device only while said switch locking relay is energized, means energized by said energy storing device controlled by further operation of said manually movable control device while said switch locking relay is energized for effecting corresponding movement of said railway track switch, and means controlled by said switch locking relay upon becoming deenergized for discharging said energy storing device.

6. Control apparatus for a railway track switch comprising, in combination, a switch locking relay which is normally energized but which is at times deenergized in response to a train on the associated railway track adjacent said switch, a manually operable switch control device, a first and a second and also a third contact closed by said manually operable switch control device in a first and a second and a third position respectively, an energy storing device, means controlled by said third contact and by said switch locking relay in its energized condition for charging said energy storing device, and means energized by said energy storing device controlled by said switch locking relay in its energized condition and by said first and second contacts for effecting operation of said switch to corresponding positions.

7. Control apparatus for a railway track switch comprising, in combination, a switch locking relay which is normally energized but which is at times deenergized in response to a train on the associated railway track adjacent said switch, a manually operable switch control device, a first and a second and also a third contact closed by said manually operable switch control device in a first and a second and a third position respectively, an energy storing device, means controlled by said third contact and by said switch locking relay in its energized condition for charging said

energy storing device, means energized by said energy storing device controlled by said switch locking relay in its energized condition and by said first and second contacts for effecting operation of said switch to corresponding positions, and means controlled by said switch locking relay in the deenergized condition for discharging said energy storing device.

8. Control apparatus for a railway track switch comprising, in combination, a manually controllable switch control device, traffic responsive means which is normally energized but which at times becomes deenergized in response to traffic conditions on an associated railway track adjacent said switch, an electrical control device, means controlled by a given operation of said manually controllable switch control device and by said traffic responsive means in its energized condition for energizing said electrical control device, and means controlled by other operation of said manually controllable switch control device and also by said traffic responsive means and said electrical control device both in the energized condition for effecting operation of said switch.

9. Control apparatus for a railway track switch comprising, in combination, a manually controllable switch control device, traffic responsive means which is normally energized but which at times becomes deenergized in response to traffic conditions on an associated railway track adjacent said switch, an electrical control device, means controlled by a given operation of said manually controllable switch control device and by said traffic responsive means in its energized condition for energizing said electrical control device, means controlled by other operation of said manually controllable switch control device and also by said traffic responsive means and said electrical control device both in the energized condition for effecting operation of said switch, and said electrical control device becoming deenergized if said traffic responsive means becomes deenergized.
